UNITED STATES PATENT OFFICE.

KRISTIAN BIRKELAND AND SAMUEL EYDE, OF CHRISTIANIA, NORWAY.

ELECTRIC FURNACE.

No. 837,277.

Specification of Letters Patent.

Patented Dec. 4, 1906.

Application filed November 10, 1904. Serial No. 232,232.

To all whom it may concern:

Be it known that we, KRISTIAN BIRKELAND and SAMUEL EYDE, subjects of the King of Sweden and Norway, residing at 5 Christania, Norway, have invented certain new and useful Improvements in Electric Furnaces; and we do hereby declare the following to be a full, clear, and exact description of the invention, such as will enable 10 others skilled in the art to which it appertains to make and use the same, reference being had to the accompanying drawings, and to letters of reference marked thereon, which form a part of this specification.

15 This invention relates to electrical furnaces used in the chemical industry to create chemical reactions under the influence of the electrical arcs.

The invention relates more especially to 20 the class of electrical furnaces described in United States Letters Patent No. 775,123, dated November 15, 1904, in which an arc is made use of which is dispersed by means of a magnetic field.

25 The object of the present invention is to improve this class of furnaces, so that they may advantageously be run with alternating currents, either for the electrodes or for the field-magnet windings, or in both.

30 It is also an object of this invention to provide means whereby it is made possible to increase the ratio between the furnace tension and the tension of the electric machinery, or, more correctly, to increase the ratio between 35 the kilowatts and the kilovoltamperes.

In the drawings, Figure 1 is a diagram showing the form of a current curve in a Birkeland furnace fed with alternating current. Fig. 2 shows an arrangement of the 40 electrodes, and Fig. 3 a detail of a modified form of the electrode-points, the electrode being hollow. Fig. 4 illustrates another form of electrode arrangement. Fig. 5 shows the general arrangement of the furnace.

45 Referring more particularly to Fig. 5, *a b* indicate the electrodes; *e*, the furnace, through the walls of which the electrodes project into the reaction-chamber. *f* is an electromagnet disposed so as to create a field in the chamber 50 around the electrodes. In this instance the electrodes are for the matter of convenience shown disposed axially in relation to the

magnetic field. They may be so disposed, although it is generally found preferable to have them disposed at right angles to the 5 lines of force. The electrode *b* is shown rotatably mounted and may be provided with a small motor *g*, which keeps it in rotation, as will be hereinafter explained more fully.

In the following it is supposed that the 6 generator *h* for delivering current to the electrodes is an alternating-current generator.

In the furnace working with alternating current the current curve has about the form indicated in the diagram, Fig. 1.

If it is attempted to increase the tension for the purpose of obtaining an increase of energy as well as arcs with increased surface by increasing the relative distance between the electrodes, the arc will soon be extinguished— 7 *i. e.*, a certain intensity of current and of magnetic field corresponds to a certain maximum distance between the electrodes. It is derived from observations that the extinction will always take place when the current 75 is about zero. If therefore it was possible to avoid extinction at this point, it might be possible to increase the tension materially without having to fear an extinction of the arc. This result may be obtained by running the furnace with a resistance in the arc, which alternates in synchronism with the current phase and in such way that the resistance has its minimum when the current 80 value is passing zero, or the variations in the 85 resistance may be of so much greater frequency than the frequency of the current that an extinction is practically excluded.

We may obtain the aim of the invention in several ways and we shall here explain three 90 different ways, one of which may be termed "mechanical," one a "magnetical," and one an "electrical" method. We may, for instance, obtain such a result by varying the relative distance between the points of the 95 electrodes in synchronism with the current phases, so as to obtain the shortest distance at the zero-points of the current curve and longer ones at the intermediate parts of the curve. Hereby is obtained an increased 100 average tension and an increased factor of energy, or, in other words, the ratio between the kilowatts and the kilovoltamperes is increased.

As it would not be suitable to have the electrodes moving to and from each other in their axial direction, in carrying out this method we prefer using electrodes or groups of electrodes rotating about an axis, whereby the necessary synchronism may be obtained by aid of a synchronous motor rotating the said electrodes or groups of electrodes.

When using electrodes of the form illustrated in Fig. 2, the electrode *a* is or may be stationary, while the electrode *b* is rotatable about its longitudinal axis, the minimum distance between the electrode-points being only a fraction of their maximum distance, and we may easily provide for any desired degree of variation of this distance simply by altering the form of the points of the electrodes.

It is advantageous to provide one or both electrodes with a plurality of points and to have the rotating electrode actuated by a synchronous motor (not shown) having a corresponding number of poles. Such an arrangement is especially suitable when tubular electrodes, as illustrated in Fig. 3, are used.

It is sometimes advantageous to make use of these tubular electrodes for the purpose of leading the gases or part of them into the furnace through the interior of the electrodes, whereby the latter are cooled.

We may also provide for an arrangement where both electrodes are stationary, but where there is placed a conductive pointed body *d* or arc-former between the said points, as illustrated in Fig. 4, the said conductive body being rotated or otherwise moved in synchronism with the current phases. The body is shown to have four points, but it may have any other form and any number of points.

The herein-described devices may also be used for furnaces running with direct current both on the electrodes and on the magnets.

In the foregoing it has been supposed that the magnetic field has a constant intensity. It is, however, possible to carry out this invention with a pulsating or variable magnetic field, such pulsation having an effect on the factor of energy substantially equivalent with the variation of the distance between the electrode.

The furnace may be worked with stationary electrodes and alternating currents both in the electrodes and in the field-magnet, obtaining thereby substantially the same result as with moving electrodes.

We may, as hereinbefore mentioned, obtain the result aimed at by way of what we call an "electrical method." This may be done by connecting the electrodes with an auxiliary circuit *k*, supplied from a source *l* through condensers *m* *n*, producing a spark

discharge of high frequency with high tension and low current strength—for instance, a Tesla current. Such discharges may be said to act as a bridge for the arc of the working current.

Having thus described our invention, what we claim as new therein, and desire to secure by Letters Patent, is—

1. In an electric furnace, the combination of means for creating a magnetic field, electrodes placed within said field, a source of alternating electric current capable of forming dispersed arcs between said electrodes, and means to vary the resistance of the current in passing between the electrodes in synchronism with the phases of the working current.

2. In an electric furnace, the combination of means for creating a magnetic field, electrodes placed within said field, a source of alternating electric current capable of forming dispersed arcs between said electrodes, and means to vary the distance between the electrodes in synchronism with the phases of the working current.

3. In an electric furnace, the combination of means for creating a variable magnetic field, electrodes placed within the said field, a source of alternating electric current capable of forming dispersed arcs between said electrodes, and means to vary the distance between the electrodes in synchronism with the phases of the field-current.

4. In an electric furnace, an electrode formed of a tubular piece of electrically-conducting material and having its ends serrated to form one or more points.

5. In an electric furnace, the combination with means for creating a variable magnetic field, a stationary and a movable electrode placed within the field, a source of alternating current capable of forming dispersed arcs between said electrodes and means to vary the distance between the electrodes in synchronism with the phases of the working current, substantially as described.

6. In an electric furnace, the combination with means for creating a variable magnetic field, hollow electrodes having eccentric arc-forming points within the field, a source of alternating current capable of forming dispersed arcs between said electrodes and means to vary the distance between the arc-forming points of the electrodes in synchronism with the phases of the working current, substantially as described.

7. In an electric furnace, the combination with means for creating a variable magnetic field, a fixed electrode whose arc-forming end is out of alignment with the axis of the electrode, a second rotatable electrode in alignment therewith and whose arc-forming end is also out of alignment with the axis thereof, a

source of alternating current capable of forming dispersed arcs between said electrodes and means to rotate the second electrode to vary the distance between the ends of the electrodes in synchronism with the working current, substantially as described.

5 In testimony that we claim the foregoing

as our invention we have signed our names in presence of two subscribing witnesses.

KRISTIAN BIRKELAND.
SAMUEL EYDE.
